UNITED STATES PATENT OFFICE.

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY.

HOBBER WITH QUICKLY-DEMOUNTABLE ARBOR SUPPORT.

Application filed June 16, 1925. Serial No. 37,447.

This invention relates to machine tools and more particularly to improved means for supporting the free end of an arbor, such, for example, as the work-supporting arbor of a 5 hobbing machine or the tool-spindle of a milling machine.

Certain machine tools having arbors or mandrels that are normally unsupported at one end have heretofore been fitted with a sup-

- 10 plemental bearing for said free end and, in certain instances, these bearings have been so constructed and arranged that they may readily be swung to an out-of-the-way position when it is desired to remove the work or 15 the tool, as the case may be. These prior devices, however, have been more or less objectionable in that they are complicated in construction and inconvenient and bothersome in operation inasmuch as when it is desired to 20 remove the support from the arbor, they require the use of wrenches not only to loosen the various bolts heretofore employed on both sides of the standard to release the supplemental arbor-support so that it may be dis- 25 placed from its operative position; but also again to tighten the bolts after the support has been shifted back to its arbor stabilizing position. Also certain of these prior devices include a swivelled element adapted to swing 30 the arbor-support out of alignment with the arbor; together with manually-operable locking-means for the swivelled element. This locking means was, of necessity, located in a more or less inaccessible position which re- 35 quired the operator to move out of his normal working position both to release the locking means before the arbor-support was swung out of alignment with the arbor and again after the support was swung back in line with 40 its operative position. A device of this nature is disclosed in my re-issue Patent No. 15,161 dated July 19, 1921; of which the present invention is an improvement.

It is therefore an object of this invention 45 to provide a simplified and otherwise improved construction for enabling the arbor-support to be moved to an out-of-the-way position and returned with greater facility than in prior constructions.

Another object of the invention is to pro- 50 vide an auxiliary arbor-support which may be secured in its arbor-stabilizing position, and unclamped therefrom, by improved means such as by a single lever so arranged

that it also may be utilized to shift the sup- 55 port out of its operative position.

Still another object is to provide an im- 60 proved form of securing means for the arbor- support and so to locate its actuating lever that the operator readily may secure or re- 65 lease the support while standing in a position where he also may shift the various other con- 70 trolling levers of the machine-tool.

A still further object of the invention is to 75 provide an arbor-support adapted to be trans- 80 ported on suitable guides provided by a sup- 85 porting-standard; thereby to separate it from the arbor, and enable it then to be swung or partially revolved into an out-of-the-way 90 position to permit ready removal of the work 95 or tool from the arbor; said partial revolution being effected by means of a swivel member having complementary guides normally aligned with the guides of the standard and adapted to receive the arbor support there- 100 from; to provide locking means to hold said swivelled member in a position where its guides coincide with the guides on the stand- 105 ard, and to provide automatically acting means to release said locking means when the arbor-support is shifted to occupy a position upon the complementary guides of said swiv- 110 elled member.

For convenience, this invention will be de- 115 scribed in connection with a hobbing machine 120 but it is to be understood that it is likewise 125 adaptable to various other types of machine 130 tools.

Other objects and advantages will be in 135 part indicated in the following description 140 and in part rendered apparent therefrom in 145 connection with the annexed drawings.

To enable others skilled in the art so fully 150 to apprehend the underlying features hereof 155 that they may embody the same in the various 160 ways contemplated by this invention, draw- 165 ings depicting a preferred typical construc- 170 tion have been annexed as a part of this dis- 175 closure and, in such drawings, like characters 180 of reference denote corresponding parts 185 throughout all the views, of which:

Fig. 1 is a side elevation of a hobbing ma- 190 chine embodying the present invention; the 195 view being taken from the side of the ma- 200 chine where the operator normally stands 205 during the operation of the machine, i. e., the 210 side where the various control levers are lo- 215 cated. Fig. 2 is a side view, partly in sec-

tion, of a bearing supporting member, later to be referred to, together with the bearing member and the means permitting it to be moved to a non-use position. Fig. 3 is a plan of Fig. 2 and Fig. 4 is a section substantially on the line 4—4 of Fig. 3 with the bearing member and its locking lever shown in elevation.

Referring more particularly to the drawings the invention is disclosed as embodied in a hobbing machine comprising a base 1 upon which is translatable supported (as by being fitted to the guides 2) a stanchion 3. The stanchion is formed at its front with vertical guideways 4 upon which is translatable mounted a cutter-carriage 5 carrying a rotatably journaled cutter-shaft 6. Also secured upon the base 1 is a bearing-block 8 within which is rotatably journaled the lower end of a work-supporting arbor 9 upon the upper end of which the work W may be secured for operation by a cutter C, secured upon the cutter shaft 6. Power to translate the cutter-carriage on the stanchion, to rotate the cutter shaft, and to rotate the work-supporting arbor may be secured from any suitable source and may enter the machine as through the shaft 10^a. Power entering the machine through the shaft 10^a may be controlled initially by a main clutch (not shown) adapted to be engaged by the operator when stationed in his normal working-position, by means of a long lever B. Both slow feed and rapid traverse mechanisms are provided for moving the cutter carriage 5 and these mechanisms may be controlled by levers h and a, respectively, also located where they are most readily accessible to the operator when in his normal working-position.

The specific mechanisms for rotating the cutter shaft, for translating the cutter-carriage and for rotating the work-supporting arbor form no part of the present invention and therefore detailed illustration and description thereof is deemed unnecessary. Hence it will suffice to designate the cutter-shaft rotating-mechanism generally as *x*, the cutter-carriage translating mechanism generally as *y* and the means for rotating the work-supporting arbor or mandrel generally as *z*. For a more complete illustration and description of this mechanism reference may be had to my pending application Serial No. 4,207 filed January 23, 1925. The main clutch 10 may also be disengaged either automatically by the movement of the cutter-carriage or manually by a lever 109 as clearly described in said application.

As hereinbefore stated, the arbor 9 is supported wholly beneath the work and, to render the arbor more rigid, so that greater precision may be secured, this invention proposes an improved form of stabilizing device for the upper end 9^a of the arbor. This stabilizing device comprises a supporting member

or standard 10 secured upon the base 1 and formed on one face with vertical guides 11 providing guideways 11^b to which is slidably fitted a bearing member 12 formed with complementary guideways 13 fitted to the guideways 11^b. The bearing-member 12 is formed at its free end 12^a with a bearing 14 adapted to receive the upper end 9^a of the work supporting arbor 9.

To rigidly maintain the bearing-member 12 on its support 10, means is provided for locking the former to the latter. This is preferably effected by forming the bearing member with relatively movable portions and by providing means for moving one portion relative to the other to cause the bearing member to grip a part of the fixed support 10 such for example as the guides 11. This conveniently may be effected by partially dividing the bearing member as by a saw-cut 15 thus forming relatively yielding portions 12^b and 12^c one of which may be flexed to cause them to grip the guides 11. With the guideways 11^b and 13 formed as shown in Fig. 3, means is provided to flex the portions 12^b and 12^c toward each other to cause them to grip the support 10 but, when other arrangements of guides are provided, as is contemplated by this invention, means may be provided to move the portions 12^b and 12^c away from each other to cause them to grip the support. The means to move the portions 12^b and 12^c toward each other may preferably comprise a bolt 16 extending through a bore 17 in said portions and having one end 17^a held against end-wise movement in the portion 12^b. The opposite end of the bolt is threaded and receives a clamping nut 18 having secured to it an actuating lever 19 so that the nut may be rotated on the screw to draw the portion 12^b and 12^c toward each other to cause them to grip the supporting member 10. The end 17^a of the bolt 16 is preferably threaded into an adjusting nut 20 to enable the bolt 16 to be shifted axially to compensate for wear on the threads of the bolt and nut 18. Through this adjustment, the parts may be kept so adjusted that the lever will always occupy the same position when the bearing member is tightly locked to the support.

The lever 19 is also adapted to serve as a convenient means for manually shifting the bearing member lengthwise of the guides 11 for a purpose later to be explained. Thus it will be seen that, when it is desired to shift the bearing member to disengage it from the end 9^a of the arbor (so that the work may be removed therefrom) the operator may grasp the lever 19 and, by a single partial rotation thereof, release the clamps that secures the bearing member to the support 10. With the clamp released, he may then push upwardly on the lever and thereby slide the bearing member upwardly onto the guides 11. Thus, the clamp-releasing and bearing-elevating

motions may be merged into a single continuous motion to effect both operations.

This employment of but a single clamp actuating lever (which is carried at the operator's side of the bearing member and which is always readily accessible to him) is one of the important features of this invention. The advantages of this construction will be better appreciated by comparing it with prior constructions such as that shown in applicant's prior reissued patent, above noted, in which the clamping of the bearing member to its support is effected by means of a plurality of bolts located at opposite sides of the supporting member and each of which must be first released and subsequently tightened for each adjustment of the bearing member. Also in the prior constructions it was necessary for the operator first to find a suitable wrench for the purpose and, as every user well knows, such tools are frequently lost or misplaced; whereas, by means of this invention, the actuating lever is always immediately available.

Another feature of this invention resides in the location of the clamp actuating and bearing member shifting lever in a position wherein the operator may readily actuate it when standing in a position where he also may readily actuate the levers B, a, h, and 109 which controls the various other operative parts of the machine-tool.

To enable the operator more readily to shift the bearing member on the guides 11, said member is preferably counter-balanced by means of a counterweight 20 secured to one end of a flexible connector 21 which passes over a sheave wheel 22 journaled on a shaft 23 and has its other end secured to the bearing member by any suitable means.

To facilitate removal of the work from the mandrel 9, this invention proposes improved means permitting the bearing member to be swung bodily out of the vertical axis of said mandrel. To this end, there is movably secured to the upper end of the supporting member 10 a supplemental member 24 provided with guides 25 similar to the guides 11 and adapted to be aligned therewith and adapted to receive the bearing member as it slides from the support 10. The member 24 may be movably supported on the member 10 in any suitable way such, for example, as by being pivoted thereto by means of a trunnion 26 secured in the member 24 and rotatably journaled in the supporting member 10. Thus, after the bearing member 12 has been shifted from the support 10 to the supplemental member, the latter may be rotated about the axis of the trunnion to remove the bearing from above the arbor.

A locking device also is provided normally to prevent relative movement between the supporting member and the supplemental member and to maintain the guides 25 in alignment with the guides 11 so that said guides cooperate to form one continuous guideway to which the bearing member is fitted. This locking device preferably comprises a bolt 27 slidably mounted in a bore 28 in the supplemental member 24 and provided with a portion 27^a adapted to enter a keeper provided by the support 10. The keeper may be in the form of a bush 29 inserted in said support 10. A spring 30 acts upon the bolt and tends to force its end 27^a into the keeper whenever the supporting member 10 and the supplemental member are so relatively arranged that the bolt is aligned with the keeper, which is the position in which the guides 25 and 11 are aligned.

This invention also provides automatically-acting means to withdraw said locking bolt from its keeper simultaneously with, and by the action of, the shifting of said bearing member to the supplemental member. Thus, the necessity of separately actuating the locking means is obviated. This is preferably effected by securing a contact-block 31 to the upper end of the bolt 27 and causing one end thereof to overlie a portion of the bearing member 12. It will, therefore, be seen that the bearing member will, in its upward movement on the guides 25, contact with the block 31 (as shown in Fig. 4) and cause the bolt end 27^a to be withdrawn from its keeper; thereby permitting the supplemental member, and the bearing member 12 carried thereby, to be swung about the axis of the trunnion.

From the foregoing, it will be perceived that this invention provides new and improved means for mounting an arbor support so that it readily may be moved to a non-use position; that it provides improved means for clamping the bearing member to its supporting member, said clamping means including a single lever so located that it may be actuated by the operator when in his normal working position and which also may be utilized to shift the bearing member on its guides; also that the improved lock-releasing means provided greatly facilitates the operation of the device. In other words the entire improved construction makes for efficiency and ease of operation and inasmuch as it is necessary to remove the arbor stabilizing bearing once for each replacement of work, it will readily be perceived that these improvements are of consequence and considerably increase the efficiency and production of the machine tool.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should

be, and are intended to be, comprehended within the meaning and range of equivalency of the following claims.

Having thus revealed this invention, I claim as new and desire to secure the following combinations and elements, or equivalents thereof, by Letters Patent of the United States:—

1. In combination, a supporting member, a supplemental member movably supported thereon; a bearing member slidably fitted to said members and adapted to be shifted from said supporting member to said supplemental member; means to lock said supplemental and supporting members; and means rendered effective simultaneously with the shifting of said bearing member to render said locking means ineffective.

2. A machine tool combining a supporting member; a main guideway upon said member; a supplemental member movably mounted upon said supporting member and provided with a supplementary guideway adapted to be aligned with the guideway of said supporting member; a bearing member fitted to said guideways and adapted to be translated from said main guideway to said supplementary guideway; means to lock said supplemental member in a position with its guideway in alignment with said main guideway; and means actuated by the translation of said bearing member to release said locking means.

3. In combination, a supporting member; a main guideway upon said member; a supplemental member pivotally arranged upon said supporting member and providing a supplementary guideway normally aligned with said main guideway; a bearing member provided with a complementary guideway adjustably mounted on the guideway on said supporting member and adapted to be translated to said supplementary guideway; locking means to prevent oscillation of said supplemental member; means actuated by the translation of said bearing member to release said locking means to permit said supplemental member and bearing member to be swung to a non-use position; and means to automatically render said locking means effective when the supplemental member is swung to a position in which its guideway is aligned with said main guideway.

4. In a machine-tool, combining a supporting member; a supplemental member pivotally arranged upon said supporting member; guideways provided by said supporting member and said supplemental member and adapted to be aligned to form a continuous guideway; a bearing member slidably fitted to said guideways and adapted first to be translated to said supplemental member and then to be swung with said supplemental member into a non-use position; a locking bolt carried by one of said members and

adapted to engage a keeper provided by another of said members to hold said supplemental member against rotation; and means actuated by the bearing member, when said bearing member is translated, to withdraw said bolt from said keeper.

5. In combination a supporting member; a supplemental member movably mounted on said supporting member; guideways provided by said supporting member and said supplemental member and adapted to be aligned to form a continuous guideway; a bearing member slidably fitted to said guideways and adapted to be shifted thereon and moved with said supplemental member into a non-use position; a locking bolt carried by one of said members and adapted to engage a keeper provided by another of said members; and a member operatively connected with said locking bolt and arranged in the path of said bearing member, whereby said bearing member, in its movement on said guideway, withdraws said locking bolt from its keeper.

6. A machine tool combining a support; a supplemental member movably mounted upon said support; a bearing member slidably fitted to said support and to said supplemental member and adapted to be shifted from said support to said supplemental member and then moved with said supplemental member to a non-use position; means to secure said bearing member to said support; said means comprising a gripping device; and a single lever to actuate said device.

7. A machine tool combining a support provided with a guideway; a supplemental member movably mounted upon said support and provided with a guideway adapted to be aligned with the first mentioned guideway; a bearing member fitted to said guideways and adapted to be translated from said support to said supplemental member and then to be shifted with said supplemental member to a non-use position; means to clamp said bearing member to said support, said means comprising a resilient connection between said bearing member and said support; and a single device to flex a portion of said resilient connection to cause said bearing member to grip said support.

8. A machine tool combining a support provided with a guideway; a supplemental member movably mounted upon said support and provided with a guideway adapted to be aligned with said first mentioned guideway; a bearing member having relatively movable portions and a guideway complementary to the guideways on said support and supplemental member and being adapted to be shifted from said support to said supplemental member and then moved with that member to a non-use position; means to clamp said bearing member to said support, said means including a single clamping device adapted to move one of said relatively mov-

able portions of said bearing member to cause it to grip said support; and a single controlling lever for said clamping device.

9. A machine-tool combining a support; a supplemental member movably mounted on said support; a bearing member slidably fitted to said support and to said supplemental member and adapted to be shifted from said support to said supplemental member and then moved with said supplemental member to a non-use position; means to clamp said bearing member to said support; and a single lever adapted to control said clamping device and to afford manual means 15 for translating said bearing member.

10. A machine-tool combining a support, a supplemental member movably mounted on said support; a bearing member slidably fitted to said support and to said supplemental member and adapted to be shifted from said support to said supplemental member; means to clamp said bearing member to said support; a single lever for controlling the action 20 of said clamp, said lever also affording means to manually shift said bearing member to said supplemental member; and means so to adjust said clamping means that the locking position of said lever is maintained constant.

11. In a hobbing machine, in combination, 30 a base; a stanchion mounted thereon; a cutter-carriage translatable mounted on said stanchion; a cutter rotatably carried by said carriage; mechanism to translate said carriage; mechanism to rotate said cutter; a main control for all of said mechanisms; control levers for said main control and for said cutter-carriage translating mechanism, said levers being all located at one side of the machine where they are readily accessible to the 35 operator when in his normal working position; a work-supporting mandrel supported from said base and provided with a free end;

means to stabilize said free end, said means comprising a support carried by said base; a bearing member adjustably mounted on 45 said support and having a portion cooperating with the free end of said mandrel; and means to lock said bearing member to said support, said locking means including a single locking lever so located and arranged 50 at the same side of the machine as said first named levers that the operator may shift all of said levers from a single position.

12. In a hobbing machine, in combination, 55 a base; a stanchion mounted thereon; a cutter carriage translatable mounted on said stanchion; a cutter carried by said carriage; mechanism to translate said cutter carriage; a controlling lever for said mechanism located at one side of said machine; a work-supporting mandrel supported by said base and provided with a free end; means to stabilize said free end, said means comprising a box-type 60 supporting member secured to said base; a supplemental member movably mounted upon said supporting member; guideways provided by said members; a bearing member slidably fitted to said guideways and having a portion adapted to receive the free end of said mandrel, said bearing member being 65 adapted to be shifted from said supporting member to said supplemental member to free it of said mandrel and then to be moved with said supplemental member to a non-use position permitting ready removal of the work 70 from said mandrel; and means to clamp said bearing member in operative position, said means including an element carried by said bearing member and located at the same side of the machine as the cutter carriage controlling lever is located.

In witness whereof, I have hereunto subscribed my name.

WILLIAM F. ZIMMERMANN.
